CLAIM

The ornamental design for a trim reveal extrusion, as shown and described.

DESCRIPTION

FIG. 1 is a perspective view of a trim reveal extrusion showing my new design.

FIG. 2 is a cross-sectional view thereof; and,

FIG. 3 is an end elevation view thereof, showing the trim reveal extrusion in an environment of use.

(Continued)

The trim reveal extrusion is shown with a symbolic break in its length. The appearance of any portion of the trim reveal extrusion between the jagged break lines forms no part of the claimed design.
